UNITED STATES PATENT OFFICE.

JOHN W. BRABANT, OF LA CROSSE, WISCONSIN.

MIXING-MACHINE.

1,391,454.

Specification of Letters Patent. Patented Sept. 20, 1921.

Application filed July 3, 1917. Serial No. 178,498.

To all whom it may concern:

Be it known that I, JOHN W. BRABANT, a citizen of the United States of America, residing at 1311 Kane street, in the city of La 5 Crosse, county of La Crosse, and State of Wisconsin, have invented new and useful Improvements in Mixing-Machines, of which the following is a specification, reference being had to the accompanying drawings, 10 which are made a part hereof.

The invention has reference to mixing machines, and more particularly to that class of mixing machines pertaining to the mixing of concrete for building and other pur- 15 poses.

The object of the invention is to provide a mixing machine of small capacity for the use of farmers and other light users of concrete, which shall be thoroughly efficient in 20 its work, rapid in its execution, substantial in construction, and that may be sold at a price that brings it within the reach of all small users of cement mixtures, and that may be easily run by hand or small powers.

Another object of the invention is to provide an improved mechanism attaching a delivery spout that may be swung into the machine to receive and discharge finished product, and swung away to carry the inner 30 end of the spout completely out of the path of the mixing material while the mixing process is going on.

While large cement mixing machines have been efficient in their work, they could not be 35 used to advantage when a small amount of work is to be done, and the necessary price has made them prohibitive for small users of concrete, and I have found that if they were produced in facsimile on a small scale, 40 they would lose their efficiency, and the material passing through the machine would clog by reason of the closeness of the splitting and mixing blades. As usually constructed they have been provided with a 45 large drum or cylinder with a number of blades circumferentially arranged to project from its interior periphery, whereby the material would be lifted and stirred in a free and very thorough manner. But, when I 50 have made machines thus arranged and copied on a small scale, I have found that the number of blades around the circumference of the cylinder are so near together that the material being worked by one blade is 55 inevitably thrown upon the material on the

succeeding blade, with the result that the material becomes clogged, the work imperfectly done and much impeded, and the machine itself has been found to require more power. Reducing the comparative sizes of 60 the blades has not overcome the difficulty. To overcome this inherent difficulty, I found by continued experiment, was only possible by reducing the number of blades, and limiting the receiving and splitting blades to a 65 pair, placed oppositely on the interior wall of the cylinder. In practice I have found that each of these blades encounters and completes its work with the material with which it is engaged in an exceedingly efficient manner, without throwing any of the material over on to the opposite blade, and that, in connection with the other improvements involved in my invention, the mixing is thor- 70oughly and rapidly accomplished, and to a 75 degree not heretofore secured in any small power or hand machine.

Figure 1 of the drawings shows a rear elevation of the machine; Fig. 1^a is a front view of the cylinder showing the orifice for receiving the material to be mixed; Fig. 2 is a side elevation; Fig. 3 is a view of the interior of the cylinder, showing the discharge cups at the near end and the receiving or splitting blades at the far end, the ends of the cylinder being omitted; Fig. 4 is an interior view of the cylinder showing the splitting blades at the near end and the discharge cups at the far end, the ends of the cylinder being omitted. Fig. 5 is a sectional view of the interior of the cylinder looking downward, showing the longitudinal overlapping relation of the splitting and the discharge blades; Fig. 6 is a detail showing the swinging mechanism for the discharge spout, 90 and a portion of the cylinder, a portion of the near supporting post being cut away and only one of the blades in the cylinder being shown; Fig. 7 is a detail plan view of one of the splitting blades looking from the center 100 toward the periphery of the cylinder; Fig. 8 is a side elevation of a splitting blade; Fig. 9 is a view of a similar blade, showing its lower edge to be elevated from the wall of the cylinder; Fig. 10 is a plan of a discharge 105 cup; Fig. 11 is a side elevation of the same cup, showing its inner end elevated away from the wall of the cylinder; Fig. 12 is a detail showing the application of power to rotate the cylinder; Fig. 13 is a diagram 110

showing the changing positions the blades assume as they move from their lowest position upwardly in a circular line.

In the drawings, A indicates the front 5 and C a side elevation of a frame, which may be of any approved construction, but which, as shown is built of steel posts 1—1 at the rear corners and 2 at the front corners, that end of the machine that receives the material being called the front; these posts may be connected together at top and bottom as desired and diagonally braced in a suitable manner. At the rear of the frame, as shown in Fig. 1, a cross bar 3 is placed intermediate the ends of the posts, and across the front of the frame is placed a corresponding cross bar.

Upon the rear bar 3 as shown in Fig. 1, a rectangular frame B is erected, consisting 20 of the upright posts 4 and 5 suitably tied by a cross bar 6 at the top and 6^a near the bottom above the bar 3 to give proper rigidity. Extending from front to rear of the frame on each side of the frame are the respective 25 shafts 7 and 8 having bearings in boxes 9 resting upon the respective cross bars 3. Toward each end of each shaft are placed bearing wheels 10 having flanges as shown, and bearing upon the wheels within the 30 flanges is a large drum or cylinder D forming the body of the mixer, and provided with the flanges 11 and 12 projecting beyond the periphery of the cylinder for support and rotation upon the wheels 10. Upon the 35 front face of the flange 12 is formed a rack wheel 12^b as shown more distinctly in Fig. 12. The front and rear ends of the cylinder are apertured with annular openings 11^a and 12^a for receiving and discharging material. 40 Upon the rear end of one side of the frame is placed a bearing box 13, which carries a shaft 14, upon the inner end of which is fixed a gear pinion 15, placed in gear with the rack wheel 12^b of the cylinder, whereby 45 rotative motion is given to the cylinder. Upon the opposite end of the shaft is fixed a belt pulley 16, and near the periphery of the pulley is attached a handle 17; with the pulley and handle the machine may be run 50 either with power or by hand.

Straps 18—18 are pivoted upon the posts 4 and 5 at 18^a, upon the lower ends of which at 18^b is hung a discharge spout 19, its pivotal attachment with the straps being placed 55 somewhat toward the inner end of the spout so that the outer end will normally drop, as shown in full lines in Fig. 6. Toward the outer end of the spout is attached a hang up hook 20 adapted for hanging over the top 60 of the frame B to hold the spout up when it is swung out of the cylinder while mixing is going on. In Fig. 6, the full lines show the outer end of the spout in lowered position, the inner end being quite a distance 65 within the cylinder in position to receive

from the rear or discharge cups material that is ready for discharge; the dotted lines show the spout swung up out of the way and hung up by the hang up hook, its inner end being practically in line with the rear wall 70 of the cylinder, and entirely removed from interference with the mixing of the material within the cylinder. It will be noticed that the spout is not hung upon a fixed pivot on the frame, as has heretofore been the practice, but upon the ends of the pivoted straps 18, and that as the inner end of the spout leaves the interior of the cylinder, it is 75 swung outward bodily with respect to the frame, whereby the inner end of the spout is brought to its position in line with the end wall of the cylinder. Heretofore it has been the custom to mount such spouts upon a fixed pivot, with the result that when mixing is being done the inner end of the spout 80 is still within the cylinder, interfering with the work being done, and causing more or less clogging of material.

In my improved machine I have placed upon the inner wall of the cylinder at its 90 receiving end, two diametrically oppositely located blades 21 and 22, which are held by suitable lug members 23 and 24. In Figs. 7, 8, 9, 10 and 11, the dotted lines 25 represent the longitudinal line of the inner wall 95 of the cylinder D. In Fig. 7 I have shown a plan view of these blades, which are in themselves alike. These blades I call "splitting blades". It will be seen that these blades are located alike at the end of the 100 cylinder, having an upward or forward curve, with respect to the direction of motion (21^a), and that this curved portion is placed close by the end of the cylinder, and upon the opposite or inner end of the blade 105 is formed a reversed curve 21^b. As shown in Figs. 4 and 5, these splitting blades are placed diagonally along the interior wall of the cylinder, from the rear end to beyond the 110 center thereof.

Fig. 13 is a diagram showing the changing position with respect to the vertical assumed by the blades as the cylinder rotates upwardly to the left, in the diagram. These blades project on a radial line from the wall 115 of the cylinder toward the axis of the same, and in the lowest position they stand vertically as shown in position "a"; as the cylinder moves around and the blades move upwardly, they assume an angular relation to a 120 horizontal line, forming a sort of cup, the pointed and forwardly curved shape of the blades entering and splitting or dividing the material in a novel and very effective manner as shown in position "b", carrying material upward therein; in position "c" the blade itself has become horizontal. Between 125 positions "a" and "c" material will begin to pour over the top sidewise, being more or less mixed in so doing, and by the time the 130

blade has reached positions "d" or "e" the material has either poured entirely off the blade to the wall of the cylinder below, or discharged longitudinally into the receiving cups 26. "a", "c" and "e" represent blades 21, that are placed in close contact with the wall of the cylinder, but "b" and "d" represent blade 22, that is raised somewhat from the wall of the cylinder, as shown in Figs. 4 and 9. This elevated splitting blade 22 not only raises material the same as blade 21 but permits it to divide somewhat, and a part of it to split and flow beneath the blade with the effect of further splitting and dividing the mass for its more complete mixture; but it, also, will permit material to pour over the top, and is completely emptied by the time it has reached the positions "d" or "e".

At the farther or discharge end of the cylinder I have placed on its wall four shorter and differently shaped blades, 26, all alike and equally spaced circumferentially, and so arranged as to receive from the ends of the blades 21 and 22 material that may flow obliquely downward from them. These blades point a little, in the direction of movement, from a radial line so as to carry material sufficiently high to easily discharge into the discharge spout when it is within the drum. At their outer ends they are formed with curves 26^a turned away from the direction of movement. Fig. 10 shows the edge of a blade substantially in plan, from which it will be seen that it is longitudinally in cup shape, and prevents material from running out at the outer end; but it, also, in ascending from the lowest position upwardly is transversely in the form of a cup, and raises material within such cup until it becomes emptied transversely.

In Fig. 11, showing the blade 26, the curve of the bottom of the blade from the point 26^e to the point 26^d, follows the curve of the wall of the cylinder, but from point 26^d inward to point 26^f, it is cut away to a straight line, leaving an angular opening between the blade and the wall of the cylinder, the purpose of which will appear later.

In Fig. 5 it will be noted that the inner ends of the blades 21 and 26 longitudinally overlap, and that transversely they are not placed in line with each other. From Figs. 3 and 4 it will be seen that there are four blades 26, equally spaced and only two of the blades 21 and 22, and the blades 21 and 22 are longitudinally out of line with all of the blades 26. Viewed from the rear the cylinder moves in clockwise direction from the bottom upwardly to the left. The curve 21^a of the blade 21 encountering the material that is thrown into the cylinder, plows into it with an upward leftward stroke. The height of the blade is not equal to the depth of the material placed in the drum. This

unmixed material the blade lifts as it plows into it, by reason of the cup-like assumption of the blade, as described, and as the blade rises material begins to flow laterally over the top, while at the same time, because of the diagonal arrangement of the blade on the wall of the cylinder, some of it begins to slide longitudinally down the blade and empty into the cup blade 26 that will be rising on the same side of the cylinder, but below the end of the blade 21. The reverse curve 21^b of the blade very much assists in the longitudinal discharge of material into the cup blades 26. By the time the blade reaches the positions "d" or "e" shown in Fig. 13, the blade will be completely emptied, and the material lifted and mixed by it will be entirely cared for before the blade 22 reaches its bottom position ready to receive its load in a similar manner. But, inasmuch as blade 22 stands away from the wall of the cylinder, as it rises, some of the material will slide backwardly beneath it and mix in a new way with material that pours over the top of the blade, to be gathered up by blade 21 as it again makes its round.

Inasmuch as the four cups 26 are of smaller capacity than the blades 21 and 22 when they are in cup position, and in their upward movement are continually throwing material over their tops and mixing it in this manner, there is a considerable amount of material there toward the bottom of the cylinder within the path of the inner ends of the cups, and inasmuch as these inner ends are elevated away from the wall of the cylinder (see Fig. 11), they are also plowing through such material, aiding very materially, and in an entirely new way, to the efficiency of the general mixing process. The overlapping of the inner ends of blades 21 and 22, also throws material into the path of the inner ends of the blades 26, insuring further and better mixing thereby.

During all of the mixing process so far described the inner end of the spout 19 has been resting in the bottom of the opening 12^a, as shown in dotted lines in Fig. 6, held thereby by the hook 20, completely out of the way of the mixing material. It will be noticed that the height of the blades is less than the depth of the ends of the cylinder from the edge of the opening to the cylinder wall, and that the spout rests across the opening so that during the mixing process none of the material can escape. When the material is thoroughly mixed, which usually occurs within about a half minute or in seven revolutions of the cylinder (I find that a speed of fourteen revolutions per minute is amply sufficient) the operator lifts the hook 20 from the top of the frame B, permitting the spout 19 to swing downwardly and inwardly as to its outer end, the inner

end swinging inwardly and upwardly as shown in full lines in Fig. 6, when as the ascending cup blades 26 begin to empty their contents, it will fall into the sloped spout and be discharged outside of the cylinder to whatever receptacle is placed to receive it. The blade 22, standing above the wall of the cylinder, permits some of the material to slide beneath it; but the blade 21, standing in close contact with the wall, lifts all of the material within the cup, and on the first revolution a considerable portion of the material passes to the cup blades 26, and on the next revolution will carry all of it to the cup blades 26, and as then all of the cups are discharging into the spout it will all be promptly discharged from the machine. As stated, I have found, and that repeatedly and continually, that about seven revolutions of the cylinder, by my novel form and arrangement of blades as above described, will make a most perfect mixture of material forming a concrete. By my improved arrangement I have therefore not only secured a greatly improved product, but have also very materially shortened the time in which successful work has heretofore been accomplished; and by reducing the number of blades receiving the material to two, I have completely avoided the interfering of one part of the material being mixed, with another part that is in the same batch in the machine; and all of the consequent clogging thereby, its imperfect mixture, and heavier draft on the machine.

It is manifest that considerable latitude in the form of construction may be made without departing from the spirit of my invention.

Having now described my invention, what I claim is:

1. In a mixing machine, the combination of a supporting frame, a horizontal mixing drum rotatively mounted thereon and having centrally placed apertures in the respective ends for receiving and discharging material, means for rotating the drum, and means within the drum for mixing material therein, comprising a plurality of blades secured to the horizontal wall of the drum, each having a forward longitudinally curved portion adjacent the receiving aperture adapted to give quick impetus to the material which it contacts, in a longitudinal direction, a succeeding portion of less curve adapted to relatively restrict the movement of the material, and an inner longitudinally depending discharge portion adapted to permit of quickened delivery therefrom, and means for discharging material from the drum.

2. In a mixing machine, the combination of a supporting frame, a cylindrical mixing drum mounted to turn circumferentially on the frame, and having end walls, with cen-

trally placed annular apertures in the ends for receiving and discharging material, means for rotating the drum, a receiving and splitting blade fixed to and projecting angularly from the interior circumferential wall of the drum and having a longitudinally straight portion with one end placed close to the receiving aperture, said end being sharply curved forwardly in the direction of movement of the drum adapted to give a quick longitudinal impetus to material encountered thereby, and means for discharging material from the drum.

3. In a mixing machine, the combination of a supporting frame, a straight cylindrical mixing drum horizontally mounted to turn circumferentially on the frame, and having end walls with centrally placed annular apertures in the respective ends for receiving and discharging material, means for rotating the drum, a receiving and splitting blade fixed to and projecting angularly from the interior circumferential wall of the drum having one end adjacent the receiving aperture, said end being longitudinally curved forwardly in the direction of movement of the drum and the opposite end curved in the opposite direction, and means for discharging material from the drum.

4. In a mixing machine, the combination of a supporting frame, a cylindrical mixing drum mounted to turn circumferentially on the frame, and having end walls, with apertures in the ends for receiving and discharging material, means within the drum for discharging material comprising a blade like cup attached to the drum at the discharge end thereof and projecting angularly from the wall, the rear portion of the blade being in close contiguity with the circumferential wall and the inner end being elevated therefrom, and means for rotating the drum.

5. In a mixing machine, the combination of a supporting frame, a cylindrical mixing drum having end walls mounted to turn circumferentially upon the frame, means for rotating the drum, the ends having apertures for receiving and discharging material, means within the drum for splitting and mixing material therein comprising a receiving blade at the longitudinally curved receiving end of the drum projecting longitudinally therein and a discharge cup at the discharge end of the drum having its inner end elevated to split and mix material in contact thereby, the inner ends of the blade and the cup overlapping longitudinally whereby the blade will laterally discharge material upon the splitting end of the cup.

6. In a mixing machine, the combination of a supporting frame, a cylindrical mixing drum having end walls mounted to turn circumferentially on the frame, means for rotating the drum, the ends having apertures

for receiving and discharging material, means within the drum for splitting and mixing material therein comprising a receiving blade at the receiving end of the drum projecting longitudinally therein and a discharge cup at the discharge end of the drum projecting longitudinally into the drum and placed circumferentially behind the receiving blade, one end thereof being elevated and formed 10 to split and mix material encountered thereby, the inner ends of the receiving blade and the cup overlapping, whereby the receiving blade will discharge material longitudinally into the cup and transversely

upon the splitting and mixing end of the 15 cup.

7. In a mixing machine, the combination of a supporting frame, a mixing drum rotatively mounted on the frame and having an aperture for receiving material therein, 20 means for rotating the drum, and means within the drum for mixing such material comprising blades secured to the drum each having a pointed and forwardly curved end for entering and dividing the material fed 25 into the drum.

JOHN W. BRABANT.
